By his Attorney *Frank Adam*

UNITED STATES PATENT OFFICE.

NORMAN WILLIAM McLACHLAN, OF ROCHESTER, GREAT LEIGHS, CHELMSFORD, ENGLAND, ASSIGNOR TO RADIO CORPORATION OF AMERICA, A CORPORATION OF DELAWARE.

TELEPHONE.

Application filed August 13, 1923. Serial No. 657,098.

To all whom it may concern:

Be it known that I, NORMAN WILLIAM McLACHLAN, a subject of the King of Great Britain, and resident of Rochester, Great Leigs, Chelmsford, England, have invented certain new and useful Improvements in Telephones, of which the following is a specification accompanied by drawings.

The object of this invention is to provide an improved loud speaking telephone.

According to this invention a soft iron reed or armature is mounted on a torsion spindle or wire between the poles of a magnet, which poles may be of channel or trough shape and in the recesses of which are two coils so arranged that the fields due to them are in the same direction, and one side of the reed is fixed to the middle of a diaphragm of mica or other suitable material which is securely clamped around its periphery.

My invention is illustrated by the accompanying drawing, in which—

Fig. 1 is a vertical cross section and Fig. 2 is a plan view of an instrument constructed in accordance therewith.

A is a diaphragm of mica the periphery of which is securely held between a ring B and an annular support C carried by a base D. The middle of the diaphragm is connected by a rod E to a soft iron reed F attached to a torsion spindle G and lying between the poles of a horse shoe magnet H which is mounted in a bearing J so that it can be adjusted by means of a nut K and spring L. The poles of the magnet are of channel or trough shape and in them are coils M, M, so arranged that the fields due to them are in the same direction. The magnet is adjusted by means of the nut K so that the reed is in a magnetically symmetrical position, a hole N being provided in the sides of the coil mounting spools to permit this adjustment. If a current be passed through the coils the reed will move about the axis of the spindle G and consequently the diaphragm will be caused to vibrate in accordance with the variations of the current.

Having described my invention what I claim is:

1. A telephone comprising a soft iron reed so mounted that it can turn between the poles of a rotatably mounted magnet, which poles

contain coils through which a current can be passed, and a diaphragm connected to the 55 reed.

2. A telephone comprising a rotatably mounted magnet, a rotatably mounted armature between air gaps in the magnet, a coil for effecting the armature, means for adjusting the angular relation between the magnet and the armature and a resonator 60 connected to the armature.

3. A telephone comprising a pivoted magnet, a concentrically pivoted armature in the air gap of the magnet, a coil surrounding the armature having its axis transverse to the direction of the air gap and a diaphragm 65 connected to the armature.

4. A telephone comprising a pivoted magnet, a concentrically pivoted armature in the air gap of the magnet, a coil surrounding the armature located between the poles of the magnet, said coil having its axis transverse to the direction of the air gap and a 70 diaphragm connected to the armature.

5. A telephone comprising a pivoted permanent magnet, a concentrically pivoted soft iron armature in the air gap of the magnet, a coil surrounding the armature having its 75 axis transverse to the direction of the air gap and a diaphragm connected to the armature.

6. A telephone comprising a magnet having air gaps, a pivoted armature in the air 80 gaps of the magnet, a coil surrounding the armature in a line joining the poles of the magnet, the axis of the coil and the axis of the armature being arranged to intersect at substantially right angles to each other, 85 means for rotatably adjusting the position of the air gaps and a diaphragm connected to the armature.

7. A telephone comprising a magnet having an air gap and channel pole pieces, a 90 coil filling the space in the channel pole pieces, an armature extending therethrough substantially parallel with the axis of the coil, said armature being mounted on a torsion spindle extending substantially in a direction at right angles to the direction of the air gap and the direction of the coil, and a diaphragm connected to the armature.

8. A telephone comprising a magnet having channel-shaped pole pieces, coils fitted 100 in said channel-shaped pole pieces, an ar-

mature extending longitudinally through a hole between the coils and a diaphragm connected to the armature.

9. A telephone comprising a magnet, a diaphragm, a pivoted armature connected to said diaphragm and disposed in a position magnetically symmetrical to the field of said magnet by means of a rotatable adjustment for the position of said magnet; a coil 10 rounding the armature and having its axis parallel thereto.

10. A telephone comprising a magnet, a diaphragm, a pivoted armature connected to the diaphragm, adjusting means for locating 15 said armature in a position magnetically symmetrical to the field of said magnet through rotation of said magnet and a coil surrounding the armature and having its axis parallel to the armature.

11. In combination a magnet, having channeled pole pieces, coil structure having a plurality of openings, fitted between the pole pieces, an armature having a torsion spindle passing through the openings.

12. In combination, a magnet having channeled pole pieces, coil spools having grooves in their ends fitted between normal members of both channeled pole pieces so that their grooves form a hole.

13. In combination, a magnet having channeled pole pieces, coil spools fitted in the pole pieces, an armature effected by the coil and means for adjusting the angular relation between the magnet and the armature without changing the tension of the armature.

NORMAN WILLIAM McLACHLAN.
